Primary Examiner — Clint A Samuel*(74) Attorney, Agent, or Firm* — Scott R. Zingerman;
David G. Woodral; James F. Lea, III(57) **CLAIM**

The ornamental design for a sports venue light as shown and described.

DESCRIPTION

FIG. 1 is a front elevation of a sports venue light of the claimed design.

FIG. 2 is a right side elevation view thereof.

FIG. 3 is a rear elevation view thereof.

FIG. 4 is a left side elevation view thereof.

FIG. 5 is a top plan view thereof; and,

FIG. 6 is a bottom plan view thereof.

The broken lines of the drawings are included for the purpose of illustrating portions of the sports venue light and form no part of the claimed design.

1 Claim, 6 Drawing Sheets(56)
